SPINNING RING

Hyatt B. Atwood and Charles Fillinger, Buffalo,
N. Y., assignors to Herr Manufacturing Com-
pany Inc., Buffalo, N. Y., a corporation of New
York

Application July 31, 1946, Serial No. 687,370

6 Claims. (Cl. 57—120)

1

This invention relates generally to the spinning art but more particularly to certain new and useful improvements in the lubrication of rings employed on spinning machines.

One of its objects is to provide the spinning ring with simple, effective and positive means for conducting or feeding lubricant to the top and inner bearing faces of the ring to insure smooth running of the traveler about the ring.

Another object of the invention is to provide a novel lubricant feed means for spinning rings which is so designed as to insure at all times an unbroken capillary feed of the lubricant to a plurality of bearing points on the traveler-engaging surfaces of the ring.

A further object is to provide a simple and effective insert-like element for facilitating the threading of the wicks in the lubricant feed ducts, for properly retaining the same in proper position, and for providing resulting capillary tubes for the lubricant.

Other features of the invention reside in the construction and arrangement of parts herein-after described and particularly pointed out in the appended claims.

In the accompanying drawings:

Figure 1 is a top plan view of a spinning ring embodying our invention. Figure 2 is an enlarged fragmentary cross section thereof taken on line II—II, Figure 1. Figure 3 is a fragmentary horizontal section taken on line III—III, Figure 2. Figure 4 is an enlarged perspective view of one of the wick-retaining inserts. Figure 5 is a similar view of a slightly modified type of insert. Figure 6 is an enlarged fragmentary top plan view of the ring showing a modified form of lubricating duct. Figure 7 is a fragmentary inside face view thereof. Figure 8 is an enlarged fragmentary sectional elevation of a spinning ring showing another modified form of the invention with the wick-retaining inserts in both the vertical and horizontal lubricating ducts.

Similar characters of reference indicate the corresponding parts throughout the several views.

By way of example, our invention has been shown in connection with a spinning ring 10 detachably mounted on an annular holder 11 which is adapted to be secured in the usual manner to the traverse bar of a spinning machine. Revolvably mounted on this ring is a wire traveler 12 which engages the top bearing face 13 and the downwardly and outwardly inclined inner bearing face 14 of the ring.

Formed in the ring is a radial or transverse

2

hole or port 15 through which lubricant is conveyed for lubricating the inner bearing face 14 of the ring, and a substantially upright hole or port 16 whose lower end intersects and communicates with the companion transverse port and through which lubricant is conveyed for lubricating the top bearing face 13 of the ring. While one set of such ports is shown in the drawings, it will be understood that any number may be employed depending upon the size of the ring. Depending from the ring-holder at one side thereof is a lubricant-receiving cup or well 17 and formed in the holder is a radial passage 18 for establishing communication between this well and the ports 15, 16, the lubricant being conveyed by capillary action through a wick 19 which extends from the bottom of the well through the passage 18 and thence into the transverse ring-port 15 where it terminates substantially flush with the inner bearing face of the ring. For the purpose of protecting this wick against the deposit of dust, lint and other foreign matter thereon, a loop-shaped cap or sheath 20 is disposed in the well to conceal the wick and seated in its loop 21 is a plug 21 of wool or the like which is in contiguous lubricant-conducting relation to the immersed portion of the wick.

Fitted in the upright port 16 of the ring to divide the same into a plurality of small tubes 30 for the capillary feed of the lubricant from the transverse port 15 to the top surface of the ring is an insert or strip 22 of metal, plastic or like material. This insert may be of any suitable shape in cross-section, and in the forms thereof shown in Figures 4 and 5, it is of a width to extend in diametrical fashion through the port 16 and of a length to extend the full length of such port and into the intersecting portion of the transverse port, as shown in Figures 2 and 3. In practice, a wick 23 is fitted in these resulting capillary tubes and for the purpose of facilitating its insertion as well as effectually retaining it in place, we fold the wick upon itself in the manner shown in Figure 2 with its free ends exposed on the top surface 13 of the ring, the insert together with the retained wick being driven into the port 16. The lower end of the insert 23 may be notched as shown in Figure 4 and as indicated at 24, to receive the folded inner end of the wick 22 and with the notch straddling the companion wick 19 and effectually presenting such wicks into contiguous unbroken, capillary lubricant-feed relation. The upper end of the insert member may be enlarged, as indicated at 25 in Figure 4, or in the manner indicated at 26 in Figure 5, to

snugly wedge or grip the upper end of the upright port 16 and thereby securely retain the insert in place. As before stated this insert may be of any suitable shape in cross-section and the wick may or may not be used, utilizing the resulting tubes for the feed of the lubricant by capillary attraction to the top bearing surface of the ring.

In Figures 6 and 7 are shown a modified form of transverse port 27 in the ring 10, wherein such port terminates at its inner end in circumferentially-extending recess 28 formed in the inner bearing face of the ring. The wick 29 in such port is divided at its free end to occupy such recess and thereby provides a more extensive lubricant-bearing point for the traveler.

In the modified form of the invention shown in Figure 8, both transverse and upright lubricant ports 15 and 16 are equipped with lubricant-conducting inserts of the type shown in Figures 1-5 inclusive, and the one in the upright port is identical therewith and identified by the corresponding reference characters. However, the insert in the transverse port is of a length to also extend through the alining ring-passage 18 and consists of the retainer strip 30 and the wick 31, the latter being folded or embraced about the inner end of the former and extending at its face end into the lubricant-wall 17.

We claim as our invention:

1. A device of the character described, comprising a spinning ring for a traveler having traveler-engaging bearing faces at its inner and top sides and having intersecting transverse and upright ports opening onto such faces, respectively, a lubricant well applied to the ring in lubricant-conducting relation to said ports, a wick in lubricant-conducting relation with said well and extending through said transverse port for feeding the lubricant to the inner bearing face of the ring, and means in said upright port defining a plurality of lubricant-conducting elements in communicating relation at their lower end with the transverse port for feeding the lubricant by capillary attraction to the top bearing face of the ring.

2. A device of the character described, comprising a spinning ring for a traveler having traveler-engaging bearing faces at its inner and top sides and having intersecting transverse and upright ports opening onto such faces, respectively, a lubricant well applied to the ring in lubricant-conducting relation to said ports, a wick in lubricant-conducting relation with said well and extending through said transverse port for feeding the lubricant to the inner bearing face of the ring, and an insert extending lengthwise through said upright port for dividing the same into a plurality of capillary lubricant-conducting tubes.

3. A device of the character described, comprising a spinning ring for a traveler having

traveler-engaging bearing faces at its inner and top sides and having intersecting transverse and upright ports opening onto such faces, respectively, a lubricant well applied to the ring in

5 lubricant-conducting relation to said ports, a wick in lubricant-conducting relation with said well and extending through said transverse port for feeding the lubricant to the inner bearing face of the ring, an insert extending lengthwise through said upright port for dividing the same into a plurality of capillary lubricant-conducting tubes, and a wick folded lengthwise about said insert and extending through the capillary tubes formed thereby.

10 15 20 25 30 35 40 45 50 55 60 65 70 75 80 85 90 95

4. A device of the character described, comprising a spinning ring for a traveler having a traveler-engaging bearing face thereon and a lubricant-conducting port opening onto such face, and an insert including a wick folded lengthwise about the same and extending lengthwise through said port.

5. A device of the character described, comprising a spinning ring for a traveler having a traveler-engaging bearing face thereon and a lubricant-conducting port opening onto such face, and an insert including a wick folded lengthwise about the same and extending lengthwise through said port, the insert having a notch at one end to receive the folded end of the wick.

20 25 30 35 40 45 50 55 60 65 70 75 80 85 90 95

6. A device of the character described, comprising a spinning ring for a traveler having traveler-engaging bearing faces at its inner and top sides and having intersecting transverse and upright ports opening onto such faces, respectively, a lubricant well applied to the ring in lubricant-conducting relation to said ports, a wick in lubricant-conducting relation with said well and extending through said transverse port for feeding the lubricant to the inner bearing face of the ring, an insert extending lengthwise through said upright port for dividing the same into a plurality of capillary lubricant-conducting tubes and provided at its lower end with a notch in register with the transverse port and its wick, and a second wick folded lengthwise about the notched end of said insert and extending through the capillary tubes formed thereby.
